UNITED STATES PATENT OFFICE.

SAMUEL MONTGOMERY KINTNER, OF PITTSBURGH, PENNSYLVANIA, ASSIGNOR, BY MESNE ASSIGNMENTS, TO WESTINGHOUSE ELECTRIC & MANUFACTURING COMPANY, A CORPORATION OF PENNSYLVANIA.

SYSTEM OF CONTROL.

Application filed May 11, 1921. Serial No. 468,570.

To all whom it may concern:

Be it known that I, SAMUEL MONTGOMERY KINTNER, a citizen of the United States, and a resident of Pittsburgh, in the county of 5 Allegheny and State of Pennsylvania, have invented a new and useful Improvement in Systems of Control, of which the following is a specification.

My invention relates to radio telegraphy 10 and more particularly to signaling systems that may be employed in connection with arc-converter systems.

One object of my invention is to provide 15 a simple and efficient means for controlling the energy radiated from radio transmission systems in which arc converters are employed.

Another object of my invention is to provide 20 a signaling system that causes an increase in the purity of the radiation from an antenna system, thereby tending to reduce interference with nearby stations.

Another object of my invention is to provide 25 an improved radio transmission system wherein the radiated waves will always have the same wave length, and wherein the oscillating currents flowing through the source of energy will be substantially constant during the dot-and-dash periods and 30 during the space periods.

One way to practice my invention is to provide 35 a local oscillating circuit which is left continuously oscillating and which is coupled to an aerial radiating circuit, the signals being effected by reducing or interrupting the currents in the aerial circuit and simultaneously inserting a sufficient resistance in series with the oscillating circuit to counteract for the relief that it 40 would get by removing the radiating circuit.

My invention may best be understood by reference to the accompanying drawings, in which:

Fig. 1 is a diagrammatic view of circuits 45 and apparatus embodying my invention, and

Figs. 2 and 3 are similar views showing modifications.

Referring to Fig. 1, I show an arc 1 50 which may be fed by means of a direct-current generator 2 through a choking coil 3 and may be supplied with blow-out coils 4 of a type well-known in the art. The arc 1 is maintained in an oscillatory condi-

tion by means of an oscillatory circuit 55 which is shunted around the arc and which includes therein a condenser 5, an inductance coil 6 and a resistor 7.

A radiating circuit, which is operatively connected to the oscillatory circuit through 60 coupling coils 6 and 8 respectively, comprises an antenna 9, the coupling coil 8 and a ground lead 10.

A switching device 11 comprises the stationary contact members 12 and 13 and the co-acting movable contact member or key 14. The movable contact member 14 is connected to the ground lead 10 and to one terminal of the resistor 7, thereby grounding the oscillatory circuit at one point. One 70 stationary contact member 12 is so connected to the antenna circuit, by means of a conductor 15, that, upon actuating the key 14 into engagement with the stationary contact member 12, a portion 16 of the 75 coupling coil 8 is shunted. The remaining stationary contact member 13 is connected to the ungrounded terminal of the resistor 7, thereby rendering the resistor 7 non-effective upon the actuation of the key 14 80 into engagement therewith.

It will, of course, be understood that any approved form of switching device may be employed to effect the results accomplished by the particular switching device 11 indicated in the drawings, and that my invention is not to be limited thereby.

Referring to Fig. 2, the arrangement shown differs from that of Fig. 1 in the provision of an auxiliary condenser 17 90 which may be placed in shunt relation to a portion 18 of the antenna inductance 8, upon actuating the key 14 into engagement with the stationary contact member 12. With the key 14 in the position just mentioned, it is apparent that the resistor 7 is rendered effective and that the antenna circuit is rendered non-effective through the simultaneous detuning of the antenna circuit and the formation of a parallel-resonant circuit therein. The parallel-resonant circuit, which includes the condenser 17, the portion 18 of the coupling coil 8 and the key 14, is so adjusted that it 95 is resonant to currents having the same frequency as the currents in the local oscillatory circuit.

Referring to Fig. 3, the arrangement

shown differs from that of the preceding figures in the inclusion of an auxiliary inductance coil 19 in series with the resistor 7 in the local oscillatory circuit, and in the 5 permanent inclusion, in the antenna circuit, of a parallel-resonant circuit 21 which is resonant to the high-frequency currents in the local oscillatory circuit when the auxiliary inductance 19 is effective.

10 In the embodiment of my invention shown in Fig. 1, signaling is accomplished by causing the key 14 to engage, successively, the stationary contact members 12 and 13. Upon actuating the key 14 into engagement 15 with the stationary contact member 13, resistor 7 is shunted to admit of the radiation of energy from the antenna circuit in a manner well known to the art.

Upon actuating the key 14 into engagement 20 with the stationary contact member 12, the resistor 7 becomes effective to maintain a constant current in the oscillatory circuit which includes the arc 1, substantially simultaneously with the detuning 25 of the antenna circuit through the shunting of the portion 16 of the antenna inductance 8.

Thus, it will be seen that, during the non-signaling periods, substantially no energy is 30 radiated from the antenna circuit.

In the modification shown in Fig. 2, the operation differs from that of Fig. 1 in the introduction of the parallel-resonant circuit in the antenna circuit to further damp the 35 oscillations during the non-signaling period. Upon interrupting the parallel-resonant circuit and simultaneously shunting the resistor 7, energy is again radiated as in the arrangement shown in Fig. 1.

40 In the modification shown in Fig. 3, signaling is effected by alternately inserting and removing the resistor 7 and the auxiliary inductance device 19 from the local oscillatory circuit. When the key 14 is 45 opened, the frequency of the local oscillating circuit is changed from the normal frequency by the additional inductance device 19, and such energy as is transferred to the antenna circuit is prevented from seriously 50 affecting it by the parallel-resonant device 21. The resistance device 7, as in the previously described modifications, serves to compensate for the considerable rise in current 55 which would otherwise occur by reason of the removal of the load drawn by the antenna circuit. The auxiliary inductance device 19 need not have a very great inductance in order to effect a suitable change in frequency to effectively stop the antenna 60 from picking up.

When the key 14 is closed, the period of the local oscillatory circuit is adjusted in tune with the antenna circuit and the latter therefore radiates energy. For all frequencies except the critical one to which the

parallel resonance device 21 is tuned, the latter will have a comparatively small impedance to currents in the radiating circuit.

The particular advantage of my invention resides in the provision of a simple 70 and efficient signaling system which is applicable to any of the well-known systems for generating high-frequency sustained alternating currents by arc convertors or thermionic devices. 75

While I have shown three embodiments of my invention, it is apparent that various changes and modifications may be made therein, without departing from the spirit and scope of my invention. I desire, therefore, that only such limitations shall be imposed thereon as are indicated in the appended claims. 80

I claim as my invention:

1. In a high-frequency transmission system, 85 an oscillatory circuit adapted to produce high-frequency oscillations of a predetermined frequency, a correspondingly tuned antenna circuit coupled thereto, said oscillatory circuit including an impedance, and means adapted to substantially simultaneously cause said impedance to become effective and said antenna circuit ineffective, and vice versa.

2. In a radio transmission system, the 95 combination with a tuned radiating circuit, an arc, means including a tuned circuit for causing said arc to oscillate and an impedance associated with said means, of means for causing said impedance to become effective and for rendering said radiating circuit substantially non-responsive to the energy traversing said arc, and vice versa. 100

3. In an electrical system, an oscillatory 105 circuit adapted to produce sustained oscillating currents, a second oscillatory circuit tuned to substantially the same frequency and operatively associated therewith, said first-named circuit including an impedance, 110 and means for substantially simultaneously rendering said second oscillatory circuit non-oscillatory and causing said impedance to become effective, and vice versa, to maintain a constant load on said first-named 115 circuit.

4. In a radio transmission system, a tuned 120 oscillatory circuit having sustained oscillating currents therein, a radiating circuit operatively associated therewith, said oscillatory circuit including an energy-consuming device, and means for rendering said radiating circuit non-radiating and for causing said energy-consuming device to become effective, and vice versa, to maintain 125 a substantially constant current in said oscillatory circuit.

5. In a radio transmission system, an oscillatory circuit having sustained oscillating currents therein, a radiating circuit op- 130

- eratively associated therewith, said oscillatory circuit including an impedance, and means for forming a parallel-resonant circuit in said radiating circuit and for substantially simultaneously causing said impedance to become effective and vice versa, to maintain a constant load in said oscillatory circuit.
6. In a radio transmission system, an oscillatory circuit having sustained oscillating currents therein, a radiating circuit operatively associated therewith, said oscillatory circuit including an impedance, and means for forming a parallel-resonant circuit in said radiating circuit and for substantially simultaneously causing said impedance to become effective, and vice versa, to maintain currents of constant amplitude in said oscillatory circuit at all times.
7. In a radio transmission system, an oscillatory circuit having sustained oscillating currents of substantially constant frequency therein, a radiating circuit operatively associated therewith, said oscillatory circuit including an impedance, and means for detuning said radiating circuit and substantially simultaneously causing said impedance to become effective, and vice versa.
8. In a radio transmission system, an oscillatory circuit having sustained oscillating currents therein, a radiating circuit operatively associated therewith, and means for substantially simultaneously altering the constants of both of said circuits while maintaining the intensity and frequency of the oscillations in said oscillatory circuit substantially constant during the signaling and non-signaling periods.
9. In a high-frequency transmission system, an antenna circuit, an oscillatory circuit coupled thereto and adapted to produce high-frequency oscillations having an approximately constant frequency under all conditions of operation, said oscillatory circuit including therein an energy-consuming device, and a circuit-changing device for causing said energy-consuming device to become either effective or non-effective and for substantially simultaneously causing said antenna circuit to become either detuned or tuned, respectively, with respect to the frequency of said oscillatory circuit.
10. In a high-frequency transmission system, an antenna circuit, an oscillatory circuit coupled thereto and adapted to produce high-frequency oscillations having an approximately constant frequency under all conditions of operation, said oscillatory circuit including therein an impedance, and a manually-operable circuit-changing device for causing said impedance to become either effective or non-effective and for substantially coincidentally causing said radiating circuit to become either detuned or tuned respectively with respect to the frequency of said oscillatory circuit.
11. In a high-frequency transmission system, the combination with an oscillatory circuit adapted to be energized by a source of oscillatory currents, of a radiating circuit coupled thereto, said radiating circuit including an inductance coil and said oscillating circuit including an energy-consuming device, an auxiliary condenser, and means for, at will either close-circuiting said energy-consuming device to render the same non-effective, or rendering said energy-consuming device effective and substantially simultaneously close-circuiting a portion of said inductance coil through said auxiliary condenser, said condenser and coil-portion forming a parallel-resonant circuit.
12. In a wireless transmission system, an arc, a circuit shunted around said arc and including a resistor, one terminal of said resistor being grounded, a radiating circuit operatively associated with said first-named circuit, and a circuit-changing device comprising a movable grounded switch-arm and two normally stationary contact members connected respectively to said radiating circuit, and to the ungrounded terminal of said resistor.
13. In a wireless transmission system, an arc, an oscillatory circuit shunted around said arc and including a resistor, a radiating circuit operatively associated with said oscillatory circuit and means including a two-point switching device operable in one position to render said resistor non-effective, and operable in the other position to cause said resistor to become effective to detune said radiating circuit and to form a parallel-resonant circuit in series with the latter.
- In testimony whereof, I have hereunto subscribed my name this 25th day of April, 1921.

SAMUEL MONTGOMERY KINTNER.
